DAVID M. PICKETT, OF DETROIT, MICHIGAN.

ENGINE-STARTING MECHANISM.

1,237,552.

Specification of Letters Patent. Patented Aug. 21, 1917.

Application filed December 9, 1916. Serial No. 135,928.

To all whom it may concern:

Be it known that I, DAVID M. PICKETT, a citizen of the United States, residing at Detroit, in the county of Wayne and State 5 of Michigan, have invented a new and useful Engine-Starting Mechanism, of which the following is a specification.

This invention relates to engine starters especially adapted for use on internal combustion engines employed for driving motor- 10 vehicles, and it consists in the novel construction and arrangement of parts as hereinafter set forth and claimed.

The invention has for its object the 15 vision of simple and efficient engine starting means which may be readily applied to motor-vehicles now in common use without interfering with the operation of the usual starting crank of the engine, which is so constructed and arranged as to be conveniently 20 accessible for manual operation from the driver's seat of the vehicle, and by means of which an automatically engageable and releasable driving connection is established 25 with the engine shaft for imparting rotations thereto to effect the initial inspirations necessary to start the engine under its own power.

A preferred structural embodiment of the 30 essential features of my invention by which the above object is attained is illustrated in the accompanying drawings, in which,

Figure 1 is a front elevation of a common type of motor-vehicle, showing my improved starter mounted thereon and associated with the engine in position for operation.

Fig. 2 is an enlarged detailed plan view 40 of the starting mechanism in connection with a portion of the engine shaft.

Fig. 3 is a central vertical longitudinal section through the starting mechanism and vehicle frame, showing the parts in the normal position.

Fig. 4 is a view similar to Fig. 3 showing the parts in the actuated position as when having completed the rotation of the shaft in starting the engine.

Fig. 5 is a transverse vertical section 50 through the parts as on dotted line 5—5 of Fig. 2.

Referring to the parts of the device by the characters of reference marked on the drawings, 1 indicates the engine shaft, 2 and 3 the side rails of the frame and 4 the dash of a common type of motor vehicle.

The main member of the starting device consists of a U-shaped sheet metal channel bar or lever 5 which is positioned to extend at an incline transversely of the frame above 60 the outer end of the engine shaft. The side walls at the lower end of the lever 5 are pivoted by a stud 6 to the extended end of an angular bracket 7 which is bolted as at 8 to the side rail 2 of the frame and the upper 65 end of this lever is freely embraced to swing vertically in the arc of a circle about the axis formed by the stud between a pair of parallel guide plates 9 secured by bolts 10 to extend at corresponding angles from opposite 70 sides of a spacing block 11 which in turn is bolted as at 12 within the side rail 3 of the vehicle frame, as best shown in Fig. 3.

Mounted to slide longitudinally within the 75 channel formed by the walls of the lever 5 is a rack-bar 13 having the teeth thereof in sliding engagement with the bottom wall of said lever, and which is retained therein by means of a series of laterally and in- 80 wardly projecting tongues 14 which are struck out of the side walls of the lever and bear at intervals upon the marginal edges of the upper face of said bar. A gear wheel 15, which is mounted on the engine shaft 1, 85 is adapted to mesh with the teeth of the rack-bar 13 through an opening 16 formed in the bottom wall of the lever 5, and as a convenient means for securing this gear it is 90 formed with an enlarged hub for reception in the open end of a flanged collar 17 which in the type of vehicle illustrated serves as the fan belt pulley, and which is secured to the engine shaft together with the gear by 95 means of the pin 18 with which the usual starting crank engages, the hub of the gear being provided with a bore 19 of sufficient diameter to permit the entrance and engagement of the starting crank with the pin in the ordinary way. (See Fig. 5). 100

The rack bar is normally held in the lower end of the channel of the lever withdrawn from engagement with the gear by means of an expansive coiled spring 20 which is secured at one end to the pivot pin 6 of said lever, and at the opposite end to an eye bolt 21 which is anchored in and extends laterally from the upper face of the rack-bar near the upper end thereof. At this point the bar extends over the gear and has the 110 teeth omitted therefrom to provide clearance for the teeth of the gear to permit it to

rotate with the shaft when the engine is running under its own power. (See Fig. 3).

As a means for imparting a forward longitudinal movement to the rack-bar to cause it to engage and rotate the gear, a cable 22 is secured at one end to the eye-bolt 21 and extending forwardly of the bar to a point near the free end of the lever is suitably secured at 23 to the reduced hub or drum 24 of a grooved pulley 25. This pulley is rotatably mounted on the stem 26 of an angular bracket 27 which is secured at its base to the rail 3 of the frame by the bolt 12. A second cable 28, which embraces the pulley at one end and is secured thereto as at 29, extends freely through a guide plate 30 on the dash 4 of the vehicle and is provided at the opposite end with a handle 31 by means of which said cable may be drawn longitudinally to rotate said pulley and drum and cause the cable 22 to wind upon the latter and draw the rack-bar longitudinally against the tension of the spring 20. (See Figs. 1 and 3).

In order to movably support the upper end of the lever between the guide plates 9 to normally position the rack-bar in registering alinement with the teeth of the gear and also to provide for imparting an upward swinging movement to said lever to raise said bar out of engagement with the gear upon the completion of its forward movement in rotating said gear so as to permit said bar to pass over the gear in returning to its normal position under the tension of the spring, I employ a shifting yoke 32 which is slidably supported within the channel of the lever upon the tongues 14 and embraces at its closed or looped end the stem of the eye bolt 21 beneath a flange or collar 33 thereon, which slidably engages the side members of the yoke to retain it against displacement. The free ends of the yoke which extend forwardly of and parallel with the rack-bar are turned outwardly at right angles to form oppositely extending lateral stems 34. These stems extend outwardly through longitudinal slots 35 formed respectively in the side walls of the lever at the upper end thereof, and said stems also extend through angular slots 36 formed respectively in the guide plates 9 and which extend at an incline from the inner ends of the longitudinal slots 35 to a point above the outer ends of said slots so that when the yoke is moved forwardly the stems 34 will be caused to slide in the slots 35 of the lever and also to travel upwardly in the inclined slots 36 of the guide plates, and in so doing will raise the free end of the lever and carry the rack bar out of engagement with the gear. Movement is imparted to drive the yoke in the forward direction by means of a stud or set screw 37 which projects from the face of the rack bar near the lower end

thereof and is adapted to engage the closed end of the yoke at a time sufficiently in advance of the completion of the forward travel of said rack-bar to carry said yoke therewith and effect the raising of the lever 70 in proper time to release the gear at the limit of the travel of said bar. (See Fig. 4). Upon the return movement of the rack-bar the stems of the yoke will remain in the uppermost portions of the inclined slots and 75 the lever will remain raised until the teeth of the bar have passed over the gear when the stem of the eye-bolt 21 will engage within the looped end of the yoke, carrying it therewith and withdrawing said stem into 80 the lower portions of said slots, thus causing the lever to swing downwardly and restore the rack bar to the normal position in registering alinement with the teeth of the gear. The spring which returns the rack bar also 85 serves to reversely rotate the drum and pulley and restore the cables to their normal positions thereon with each operation of the device, and these operations for reciprocating the rack-bar may be repeated as many 90 times as may be required in effecting the necessary rotations of the shaft to start the engine.

It is obvious that changes may be made in the structural details without departing from the essential features of the invention, which is presented herewith as including all such changes and modifications as properly come within the scope and meaning of the following claims.

I claim:

1. In an engine starter, the combination with an engine shaft having a gear thereon, of a lever pivoted to swing toward and from said gear, an inclined guide for the swinging end of said lever, a rack-bar slidably carried by said lever and adapted to engage said gear, means to yieldably restrain said rack-bar normally retracted, manually operable means for imparting movement to said rack-bar, and means slidably engaging said lever and said inclined guide and engageable by said rack-bar for imparting movement to swing said lever with the movement of said bar.

2. In an engine starter, the combination with an engine shaft having a gear thereon, of a lever pivoted to swing toward and from said gear, an inclined guide freely embracing the swinging end of said lever, a rack-bar slidably carried by said lever and adapted to engage said gear, a yieldable member restraining said rack-bar normally retracted, a shiftable member engageable by said rack-bar slidably engaged with said lever and with said inclined guide and acting thereon to raise said lever through movement of said rack-bar, and manually operable means for imparting movement to said rack-bar.

3. In an engine starter, the combination

- with an engine shaft having a gear thereon, of a lever pivoted to swing toward and from said gear, a guide for the swinging end of the lever having an inclined bearing surface, a rack-bar slidably carried by said lever and adapted to engage said gear, means to yieldably restrain said rack-bar normally retracted, manually operable means for imparting movement to said rack-bar, and a 5 10 15 20 25 30 35
- slidable member supporting said lever in engagement with said inclined bearing surface and engageable with said rack-bar for receiving the movement thereof to swing said lever.
4. In an engine starter, the combination with an engine shaft having a gear thereon, of a lever pivoted at one end to swing toward and from said gear, a guide member freely embracing the swinging end of said lever and having an inclined way therein, a rack-bar slidably carried by said lever and adapted to engage said gear through movement in one direction, means to yieldably restrain said rack-bar normally retracted, a shiftable member engageable by said rack-bar slidably engaged with said lever and with the inclined way of said guide and acting thereon to raise and lower said lever with the respective movement of said rack-bar in opposite directions, and manually operable means for imparting movement to said rack-bar.
5. In an engine starter, the combination with an engine shaft having a gear thereon, of a lever pivoted to swing toward and from said gear, a fixed guide for the swinging end
- of said lever having inclined ways therein, a rack-bar slidably carried by said lever and adapted to engage said gear, an elastic member restraining said rack-bar normally retracted, a shiftable member slidably engaged with said lever and with said inclined ways, means on said rack-bar engageable with said shiftable member for imparting movement thereto with the movement of said rack-bar, and manually operable means for actuating said rack-bar.
6. In an engine starter, the combination with an engine shaft having a gear thereon, of a lever pivoted to swing toward and from said gear and having a longitudinal channel therein, a fixed guide embracing the free end of said lever and having inclined slots in the sides thereof, a rack-bar slidably carried in the channel of said lever and having lateral projections at opposite ends thereof, said rack-bar being adapted to engage said gear with movement in one direction, a yoke slidably supported in the channel of said lever and engageable at its looped end alternately by said lateral projections, the free ends of said yoke being slidably engaged with said inclined slots, manually operable means for imparting movement to said rack-bar to rotate said gear and actuate said yoke to raise said lever, and a spring for retracting said rack-bar and yoke to restore said lever to the normal position.

In testimony whereof I sign this specification.

DAVID M. PICKETT.
